CENTRIFUGAL FAN

Carl O. Bergstrom, Boston, Mass., assignor to
B. F. Sturtevant Company, Boston, Mass.

Application April 13, 1938, Serial No. 201,769

8 Claims. (Cl. 230—274)

This invention relates to centrifugal fans and relates more particularly to centrifugal fans which may be supported from a ceiling and which draw air from above the ceiling through an opening therein and which discharge the air into the space below the ceiling.

This invention provides a quiet, efficient fan particularly suitable for the pressure ventilation of railway passenger and rapid transit cars. In such cars, outdoor air may be admitted into the space between the roof and ceiling; the ceiling may be apertured at several points along a central longitudinal line, and the fans of this invention may be attached to the ceiling so as to draw the outdoor air through the apertures and to discharge it into the cars.

An object of the invention is to provide pressure ventilation for passenger vehicles.

Another object of the invention is to provide a quiet, efficient fan for supplying air without drafts into a space below same.

Other objects of the invention will be apparent from the following description taken together with the drawing.

The invention will not be described with reference to the drawing, of which:

Fig. 1 is a plan view looking downwardly, of one embodiment of a fan of the invention;

Fig. 2 is a side elevation, partially in section, of the fan of Fig. 1, and

Fig. 3 is a plan view looking upwardly, of the fan of Figs. 1 and 2.

The fan wheel is made up of the inclined blades 5, the side plate 6 to which the front edges of the blades 5 are attached as by welding, the back plate 7 to which the back edges of the blades 5 are attached, and the hub 8. The vertical shaft 9 of the motor 11 extends through the hub 8 and has a threaded lower portion upon which is screwed the nut 10 which retains the hub 8 upon the shaft 9.

The ceiling 12 is apertured and the fan assembly is mounted within the aperture with the motor 11 above the ceiling and with the fan wheel extending below same.

The metal drum member 13 is formed with the lower, outwardly extending, horizontal flange 14 and the upper inwardly extending, horizontal flange 15. The motor 11 and the fan wheel it supports, are supported by means of the spider member 16 which is attached to the flange 15 by the bolts 17. The upper portion of the inlet member 28 is welded to the inner portion of the flange 15. The lower flange 14 and the upper

annular member 18 are attached to the lower side of the ceiling 12 by means of the bolts 19.

The circular sheet member 20 forms the lowermost portion of the assembly and is mounted directly and centrally below the fan wheel. Welded to the member 20 are the machine screw receptacles 21 which receive the threaded lower ends of the machine screws 22 which pass through apertures in the flange 14 and upper annular member 18 and which are supported from the flange 14.

The three spacing cylinders 23, 24 and 25 are mounted on each machine screw 22 between the upper annular member 18 and the circular sheet member 20. The annular diffusing member 26 is supported between the cylinders 23 and 24 and a similar annular diffusing member 27 is supported between the cylinders 24 and 25.

In operation, the fan draws air from above the ceiling 12, through the inlet 28 and the air is discharged between the annular members 26 and 27 and between them and the upper annular members 18 and the lower circular sheet 20. The horizontally extending circular member 20 and annular members 18, 26 and 27 separate the air discharged from the fan into horizontal laminations and cause it to be projected substantially horizontally to a substantial distance from the fan before it falls into the underlying space, thus enabling considerably larger volumes of air to be discharged without drafts, than has been possible heretofore.

While one embodiment of the invention has been described for the purpose of illustration, it should be understood that the invention is not limited to the exact apparatus and arrangement of apparatus disclosed herein, as many departures may be suggested by those skilled in the art without departing from the spirit of the invention.

What is claimed is:

1. A fan assembly comprising a vertical shaft, an electric motor connected to the upper end of said shaft, a centrifugal fan wheel on the lower end of said shaft, means comprising a plurality of substantially horizontal, annular members around said wheel for dividing the air discharged by said wheel into a plurality of superimposed, substantially horizontal, air streams, a supporting member having an upwardly extending portion and two substantially horizontal portions, an inlet shroud supported from one of said horizontal portions, and means for supporting said annular members in spaced relationship, from the other of said horizontal portions.

2. A fan assembly comprising a vertical shaft, an electric motor connected to the upper end of said shaft, a centrifugal fan wheel on the lower end of said shaft, a substantially horizontal, circular sheet member below said wheel, a substantially horizontal, annular member around said wheel, said members serving to divide the air discharged by said wheel into a plurality of superimposed, substantially horizontal layers, a 5 supporting member for said assembly having an upwardly extending portion and having an inwardly and an outwardly extending substantially horizontal portion, an inlet shroud attached to said inwardly extending portion, means 10 for supporting said motor from said inwardly extending portion, and means for supporting said annular and circular members from said outwardly extending portion.
3. A fan assembly comprising in combination, 15 a motor having a vertical, downwardly extending shaft, a centrifugal fan wheel on the lower end of said shaft, an inlet shroud, an annular air deflecting member around said wheel, a circular sheet, deflecting member below said wheel, and supporting means having external attaching 20 means and having upwardly extending means supporting said motor above said attaching means and having downwardly extending means supporting said deflecting members below said 25 attaching means.
4. A fan assembly comprising in combination, 30 a motor having a vertical, downwardly extending shaft, a centrifugal fan wheel on the lower end of said shaft, an inlet shroud, an annular air deflecting member around said wheel, a circular sheet, deflecting member below said wheel, and supporting means having external attaching 35 means and having upwardly extending means supporting said motor and said shroud above 40 said attaching means and having downwardly extending means supporting said deflecting members below said attaching means.
5. A fan assembly comprising a motor having 45 a downwardly extending shaft, a centrifugal fan wheel on the lower end of said shaft, an annular
- air deflector around said wheel, a circular sheet deflector below said wheel, a supporting member having an upwardly extending portion and an inwardly extending and an outwardly extending portion, means for supporting said motor from said inwardly extending portion, and means for supporting said deflectors from said outwardly extending portion. 5
6. A fan assembly comprising a motor having a downwardly extending shaft, a centrifugal fan wheel on the lower end of said shaft, an annular air deflector around said wheel, a circular sheet deflector below said wheel, an inlet shroud, a supporting member having an upwardly extending portion and an inwardly extending and an outwardly extending portion, means for supporting said motor and said shroud from said inwardly extending portion, and means for supporting said deflectors from said outwardly extending portion. 10
7. A fan assembly comprising a motor having a downwardly extending shaft, a centrifugal fan wheel on the lower end of said shaft, an annular air deflector around said wheel, a circular sheet deflector below said wheel, a supporting member having an upwardly extending portion and an inwardly extending and an outwardly extending portion, means for supporting said deflectors from said outwardly extending portion, and an inlet shroud forming an extension of said inwardly extending portion. 15
8. A fan assembly comprising a motor having a downwardly extending shaft, a centrifugal fan wheel on the lower end of said shaft, an annular air deflector around said wheel, a circular sheet deflector below said wheel, a supporting member having an upwardly extending portion and an inwardly extending and an outwardly extending portion, means for supporting said deflectors from said outwardly extending portion, means for supporting said motor from said inwardly extending portion, and an inlet shroud forming an extension of said inwardly extending portion. 20
